Primary Examiner — Catherine Ho

(57) **CLAIM**

The ornamental design for a medical product storage device, as shown and described.

DESCRIPTION

FIG. 1 is a top perspective view of the medical product storage device showing our new design;

FIG. 2 is a bottom perspective view thereof;

FIG. 3 is a front elevation view thereof;

FIG. 4 is a back elevation view thereof;

FIG. 5 is a side elevation view thereof;

FIG. 6 is the opposite side elevation view thereof;

FIG. 7 is a top plan view thereof; and,

FIG. 8 is a bottom plan view thereof.

The broken lines show portions of the article that form no part of the claimed design.
